(57) **CLAIM**

I claim the ornamental design for a pair of scissors, as shown and described.

DESCRIPTION

FIG. 1 is a perspective view of a pair of scissors according to a first embodiment of my design;

FIG. 2 is a front view of the same pair of scissors;

FIG. 3 is a rear view of the same pair of scissors;

FIG. 4 is a left side view of the same pair of scissors;

FIG. 5 is a right side view of the same pair of scissors;

FIG. 6 is a top plan view of the same pair of scissors;

FIG. 7 is a bottom view of the same pair of scissors;

FIG. 8 is a perspective view of a pair of scissors according to a second embodiment of my design;

FIG. 9 is a front view of the pair of scissors according to the second embodiment;

FIG. 10 is a rear view of the pair of scissors according to the second embodiment;

FIG. 11 is a left side view of the pair of scissors according to the second embodiment;

FIG. 12 is a right side view of the pair of scissors according to the second embodiment;

FIG. 13 is a top plan view of the pair of scissors according to the second embodiment; and,

FIG. 14 is a bottom view of the pair of scissors according to the second embodiment.
